UNITED STATES PATENT OFFICE.

MIERS CORYELL, OF NEW YORK, N. Y.

STEAM-BOILER FURNACE.

SPECIFICATION forming part of Letters Patent No. 313,992, dated March 17, 1885.

Application filed June 27, 1884. (No model.)

To all whom it may concern:

Be it known that I, MIERS CORYELL, of the city and State of New York, have invented an Improvement in Steam-Boiler Furnaces, of 5 which the following is a specification.

In steam-boilers, particularly marine boilers containing horizontal tubes, it is usual to construct the fire-chamber and the flue behind the bridge-wall as wide as possible, in order 10 that the heat may rise around the sides of the boiler nearly as high as the water-level. Horizontal tubular boilers of this character are very liable to foam, and many efforts have been made to check and lessen this difficulty 15 without success. In boilers of this character the horizontal tubes are usually placed as closely together as consistent with the requisite strength of the tube-sheets. I have discovered that the primary cause of the foaming in these steam-boilers is the lack of circulation, and the formation of steam-bubbles upon the pipes and upon the entire lower surface of the boiler, so that these, rising simultaneously, disintegrate the mass of water, and 20 cause the whole to rise as foam, and the water cannot circulate downwardly again because the tubes are so close together that they act as a septum to hold up the mass of water jointly with the upwardly-rushing steam, and previous 25 to the foaming there is such a small column of water above the tubes that the rush of steam easily lifts the same.

To insure a rapid circulation of the water in the boiler, and thereby cause the circulation to 30 convey with it the bubbles of steam and throw them off from the surface, is the object of my improvement.

I have found in practice that when the sides of the fire-chamber are drawn in, and the flue or combustion chamber below the boiler is made sufficiently narrow to lessen the area exposed to the action of bottom heat to about one-third the circumference, then the sides are shielded so far down that the heat does not 40 cause any ascending columns of water at the sides of the boiler, but on the contrary allows the water to circulate downwardly at the sides of the boiler, and to rise near the middle and pass upwardly and outwardly among the 45 ranges of horizontal flues, and in this manner 50 the efficiency of the boiler is promoted, and

the difficulty of foaming prevented by concentrating the bottom heat upon a narrower part of the boiler; and this is no injury to the boiler, because the gases passing through the 55 tubes give their heat off to the surrounding water, which water takes up the heat more rapidly when continuously in contact than it does when frequently separated by the steam as the boiler foams.

In the drawings, Figure 1 is a longitudinal section of the boiler and furnace. Fig. 2 is a cross-section through the furnace, and Fig. 3 is a sectional plan below the line *xx*.

The boiler A is provided with the tubes B 60 and smoke-flue D, as usual, and the furnace-door C, grate-bars E, and ash-pit F are of ordinary construction. The sides of the furnace are contracted from the grate-bars to the sides of the boiler either at an inclination, as seen 65 at *g*, or as a segment of an arch, as seen at *g'*, and the side walls, *h*, beyond the bridge-wall *k*, come into contact with the boiler, and are vertical below the said point of contact, so that the space between the lines of contact *i i* 70 of the brick-work with the cylindrical shell of the boiler include only about ninety degrees to one hundred and twenty degrees of such cylinder, instead of about one hundred and eighty degrees, as heretofore usual.

The consequence of this mode of constructing the furnace and combustion-chamber beyond 75 is that the water in the boiler at the side portions is not exposed to external or bottom heat, and descends as indicated by the arrows, and 80 the water in the middle part of the boiler ascends and passes outwardly; hence the circulation is rendered very rapid, and the steam is given off, and foaming is avoided because 85 the water is compelled to circulate instead of rising in a mass by the action of the steam-generator.

In instances where there is a case and vertical tubes inside the water-space the heat 90 acts upon the thin layer of water between the 95 boiler-shell and the inner case so that the downward circulation at the boiler-shell is interferred with, and the water is liable to foam. The same risk exists where the flues are horizontal and there are water-legs opening into the sides of the boiler.

I claim as my invention—

The combination, with a steam-boiler having a mass of contiguous horizontal tubes passing through the same, and a fire-chamber, bridge-wall, and flue beneath the same, 5 of side walls to the fire-chamber and flue that are contracted and inclose the sides of the boiler, so as to protect the same from heat, and allow the water in the boiler to circulate downwardly at the sides and rise upwardly

between the tubes, and thereby prevent forming, substantially as set forth.

Signed by me this 23d day of June, A. D. 1884.

MIERS CORYELI.
